UNITED STATES PATENT OFFICE.

FRANKLIN CHATFIELD, OF MINNEAPOLIS, MINNESOTA, ASSIGNOR TO THE MUNSING-WEAR CORPORATION, OF MINNEAPOLIS, MINNESOTA, A CORPORATION OF MINNESOTA.

BLOOMERS AND METHOD OF MAKING THE SAME.

Application filed October 8, 1924. Serial No. 742,427.

The object of my invention is to provide a woman's undergarment of the bloomer type in which the maximum of economy may be effected in the employment of material used in making the garment; second, the cut of the garment allows for extreme simplicity in the formation of seams and hence in the amount of sewing required; third, the sewing provides for an extremely simple manner of reinforcing the garment at the point where subjected to the greatest strain; fourth, the garment is marked by simplicity in the gore construction, (that is, gores may be assembled before being incorporated into the garment), and by the length of the "uprise" or seat portion from the crotch point to the waistband; fifth, the garment is made with all seams straight making it less difficult in the matter of production; sixth, the leg sections and the gores are all cut from a knit tubing without waste of material.

Other objects of the invention will appear from the following detailed description.

The invention consists generally in the construction and arrangement of the gores interposed between the leg sections of the garment all as hereinafter described and particularly pointed out in the claims.

In the accompanying drawings forming part of this specification,

Figure 1 is a view of the garment inverted with the leg portions separated showing the relative position of the gores;

Figure 2 is a front view illustrating the garment with the wearer in a squatting position;

Figure 3 is a rear view of the garment in use with the wearer in a stooping position;

Figure 4 is a side view of the garment in use showing the wearer with one leg elevated and illustrating the smooth appearance of the garment in this position;

Figure 5 is a view of a section of tubing, showing in dotted lines the manner of cutting the leg sections therefrom without waste;

Figure 6 is a view of the leg sections as cut from the tube in Figure 5, but turned at right angles with reference thereto so as to indicate by the dotted line how the tube section is severed to provide the two leg sections;

Figure 7 is a view of a section of tubing from which the crotch or center gore is cut;

Figure 8 is a view of a similar section

of tubing from which the leg gores are formed;

Figure 9 illustrates the relative arrangement of the crotch and leg gores for a standard garment;

Figure 10 shows a similar arrangement of the gores in a garment adapted for a stout person.

In the drawings, 2 and 3 represent the leg sections of the garment. These sections are preferably obtained by taking a piece of knit tubing and severing it along transverse lines A and B, (see Figure 5), to form tubular sections C. These sections determine the length of the garment when completed as shown in Figure 1. The line A is

cut on a slight diagonal, as shown, in order to provide a better fitting garment at the waist line. Each section C, after it has been cut from the tubing, is turned at right angles from the position in which it is cut, and is flattened as shown in Figure 6. It is then longitudinally severed along the dotted line D, thereby forming the two leg sections

2 and 3. By referring to this figure, it will be noted that by cutting the upper ends of the leg sections on a diagonal, as indicated at A, the front top edge of the section C, after having been turned and positioned as shown in Figure 6, will be relatively lower than the back edge thereof, as indicated at

4. Thus, when the two leg sections 2 and 3 are assembled in the garment the waist line of the garment will be lower at the front than it is at the back, thereby providing a better-fitting garment around the waist line.

An important feature of this invention resides in the gore construction of the garment. As shown in the various figures of the drawings, the garment preferably comprises the two leg sections 2 and 3, a crotch gore 5 and the leg gores 6. The center or crotch gore 5 is substantially diamond-shape in form and is preferably cut from a knit tubing as indicated by the dotted lines in

Figure 7. By referring to the above figure, it will be noted that when cutting the crotch gore as above stated, there will be no waste of material. This gore is designed particularly for use in garments of standard size, the long point or end 7 thereof being adapted to extend up the back of the garment

while the shorter point or end 8 will extend through the crotch and up the front, both points merging into the seams 9 and 10 at

100

105

110

the rear and front of the garment, as shown in Figures 1 and 3. The leg gores 6 are similarly cut from a knit tubing as indicated by the dotted lines in Figure 8. These side 5 or leg gores 6, when cut from the tubing, will be substantially triangular in shape as shown in Figure 9. In the construction of the garment the side gores 6 are first stitched or secured to the short end of the crotch 10 gore 5 as shown in Figure 9, after which the assembled gores are incorporated in the garment and stitched to the leg sections 2 and 3 as shown in Figures 1, 2, 3, and 4.

Another feature in the construction of this 15 garment resides in the simplicity of the seams and the simple manner in which the different parts of the garment may be stitched or sewed together. It will be noted that there are no curved or irregular seams, 20 all seams being substantially straight, thereby greatly simplifying the construction of the garment. By the use of the novel gore construction above described, the garment when completed will have the requisite full- 25 ness in the legs and seat to provide a smooth-fitting garment. Also by the use of the crotch gore 5 and leg gores 6, all strain will be practically eliminated from the seams of the garment as the arrangement of the gores 30 will provide the necessary flexibility to the garment and will absorb substantially all of the strain as particularly shown in Figures 2 and 4.

On a heavier or stouter person, it may be 35 desirable to vary the width of the leg gores and also to slightly change the design of the center gore 5 from that shown in Figure 9. The relative size of the gores for a standard size garment is illustrated in Figure 9 where 40 one point of the crotch gore is shown of greater length than the other point. In Figure 10, there is shown a slightly modified construction wherein the center or crotch gore 11 is substantially symmetrical in form; 45 that is, the tapered portions of the gore on each side of the center are of practically the same length. With this form of crotch gore, I prefer to provide a wider form of leg gore 12, which, cooperating with the crotch 50 gore, provides a greater fullness in the crotch and seat of the garment and adapts it particularly for a stout person. With this form of gore construction the points of the leg gores are preferably cut off as shown so that 55 they will not come to a point as shown in the previous figures, but the lower or bottom end 13 thereof, when the gore is assembled in the garment, will form a portion of the lower end of the leg section as indicated by the dotted line 14 in Figure 4. The 60 type of gore construction shown in Figure 10 is therefore of particular value in the use of a garment designed for a stouter person as by its use the side gores constitute substantially the entire inner portion of each

leg of the garment which is usually subjected to the greatest amount of wear.

This novel garment may also readily be reinforced by simply using two or more thicknesses of material in the construction 70 of the leg gores and also in the construction of the crotch gore, if desired, as this portion of the garment is usually subjected to the greatest amount of wear.

An undergarment made in this way will 75 allow perfect freedom of the limbs of the wearer without pulling of the seams of the garment, chafing the wearer or causing discomfort in any way, the smooth fit of the crotch portion being plainly indicated in 80 Figures 2, 3 and 4 where the garment is shown on a living model. The diamond-shape crotch gore joining the wider ends of the leg gores provides the proper and desired fullness at this point in the garment, 85 allowing the wearer to assume a stooping, squatting or standing position with one leg elevated without any inconvenience or discomfort or pulling, or straining of the garment. The symmetrical form of the gores 90 allows for cutting them out of a fabric tube with practically no waste of material, thus effecting considerable economy in the manufacture of the garment. The fullness of the garment in the crotch is of course supplemented in allowing freedom of movement of the limbs of the wearer by the natural stretch of the knit fabric from which the garment is made. The fabric though closely woven will yield when pull is applied thereto 100 and allow the garment to be fitted smoothly and afford sufficient stretch so that even under extreme strain the seams will not be opened or the fabric damaged or broken. By suitable variations in the width and relative arrangement of the crotch and leg gores, the garment can readily be adapted to fit a slender or stout person as desired.

I have shown the invention made up from 105 knit tubing but do not confine myself to the use of such material, as in some cases a flat knit or woven fabric may be used.

I claim as my invention:

1. A woman's undergarment comprising 110 leg sections, a substantially diamond-shaped gore inserted into the crotch of the garment between said leg sections and having its edges united to the longitudinal edges of the fabric composing the leg sections and extending through the crotch up into the front and back seams of the garment, and leg gores formed separately from said diamond-shaped gore and tapered in form having their wider ends stitched to the opposite converging edges of one end of said crotch gore, and extending down the leg seams from said crotch gore and cooperating therewith to provide necessary crotch fullness.

2. A woman's undergarment comprising 115 leg sections composed of longitudinally

divided tubular fabric, a substantially diamond-shaped gore inserted into the crotch of the garment between said leg sections and having its edges united to the longitudinal edges of the fabric and extending through the crotch up into the front and back seams of the garment, the point of maximum width of the gore being in the rear of the vertical axis of the garment, and leg gores formed 10 separately from the diamond-shaped gores tapered in form having their wider ends stitched to the opposite edges of one end of said crotch gore and extending down the leg seams from said crotch gore, and cooperating 15 with said crotch gore to provide necessary crotch fullness.

3. The method of making an undergarment for women comprising cutting transversely into proper length and in one piece 20 from a fabric strip, the portions composing the body and leg portions of the garment, dividing by transverse straight lines a strip into substantially diamond-shaped pieces, then attaching triangular portions to opposite side edges of the diamond-shaped pieces 25 to form a gore and attaching the gore thus formed in the crotch of the garment formed by the first two portions.

4. The method of forming women's 30 bloomers which comprises cutting transversely a long tubular portion of material, and splitting it lengthwise on one side to form the legs of the garment, cutting a portion of material by straight transverse lines 35 to form diamond-shaped and triangular portions, stitching the triangular portions to opposite edges of the diamond-shaped portions to form the crotch fullness and stitch-

ing the crotch to the leg portions to provide requisite fullness and complete the garment. 40

5. A woman's undergarment comprising leg sections, a substantially diamond-shaped gore inserted into the crotch of the garment between said leg sections and having one end extending up the front of the garment 45 and the other up the back thereof between the leg seams, whereby the widest point of said gore will be adjacent the vertical axis of the garment, and substantially triangular leg gores formed in separate pieces from 50 the diamond-shaped gore having their wider ends stitched to the opposite converging edges of one end of said crotch gore and extending down the opposite leg seams from said crotch gore and cooperating therewith 55 to provide the requisite crotch fullness.

6. A woman's undergarment comprising leg sections, a gore tapered from a point near the middle thereof toward each end, one end being adapted to extend up the front of the garment and the other up the back thereof between the leg seams, whereby the widest point of said gore will be adjacent the crotch, and leg gores tapered from 60 one end toward the other and formed in 65 separate pieces and having straight edges at one end adapted to fit and be secured to the opposite tapered edges of one end of said crotch gore and extending down the opposite 70 leg seams from said crotch gore and cooperating therewith to provide the requisite crotch fullness.

In witness whereof, I have hereunto set my hand this 6th day of October, 1924.

FRANKLIN CHATFIELD.
